Attorney

UNITED STATES PATENT OFFICE.

ALBERT HOSSACK, OF JOHANNESBURG, TRANSVAAL, SOUTH AFRICA, ASSIGNOR OF ONE-HALF TO THE VICTORIA FALLS AND TRANSVAAL POWER COMPANY LIMITED, OF JOHANNESBURG, TRANSVAAL, SOUTH AFRICA.

APPARATUS FOR REMOVING ASHES AND CLINKERS FALLING FROM THE GRATES OF BOILERS OR OTHER FURNACES.

Application filed January 12, 1922. Serial No. 528,731.

To all whom it may concern:

Be it known that I, ALBERT HOSSACK, subject of the King of Great Britain, residing at 43 Observatory Avenue, Observatory, 5 Johannesburg, Transvaal, South Africa, have invented certain new and useful Improvements in Apparatus for Removing Ashes and Clinkers Falling from the Grates of Boilers or Other Furnaces, of which the 10 following is a specification.

This invention relates to apparatus for the removal of ashes and clinkers falling from the grates of boilers or other furnaces of the type in which the refuse material is 15 discharged under a water seal into a container and removed by mechanical means.

The object of the invention is to provide an installation which is economical in first cost and upkeep and which ensures that the 20 refuse material shall be discharged from the water in a comparatively dry state so that it can be handled easily without further treatment. A further object is to avoid grit and water coming into contact with any 25 bearing surface.

According to this invention a wheel fitted with vanes, paddles or the like is arranged, in conjunction with a tank designed to receive the ashes falling from the furnace, in such a way that the bearing is well clear of the surface of the water so 30 that there is no possibility of access of grit or water to the bearing surfaces and so that the device discharges the refuse practically free from water over the edge of the tank. The action of the wheel is a lifting action 35 as distinct from a scraping action and is not wholly dependent on the shape of the tank in which it revolves. Moreover matters are so arranged that the water in the 40 tank is kept cool by an inlet pipe and an overflow, in such a way, that the flow of water from the tank is independent of and distinct from the discharge of the refuse. 45 The discharged material can be removed by hand, but preferably it is caused to fall into a longitudinal conveyor running alongside or underneath the tanks. If considered desirable more than one tank can be used with 50 each boiler or furnace.

The wheel may be driven either continuously by gearing or intermittently by a

ratchet and pawl mechanism, the motion being obtained from the reciprocating motion of a rope or rod to which the pawl 55 levers are detachably secured, the rope or rod extending along the entire length of a row of boilers and imparting motion to any number of wheels.

The rope or rod may conveniently be 60 driven by the same gear which operates the longitudinal conveyor or by any other appropriate means.

This invention effects great saving in 65 labour, and permits of the ready transfer- ence of the ash and clinker to any convenient site.

The invention is illustrated in the accompanying drawings in which;

Fig. 1 shows a longitudinal section of 70 an apparatus in use for one boiler, and

Fig. 2 shows a cross section.

a is a tank fitted beneath ash hoppers *b* of a boiler and filled with water to a constant level which is maintained by an overflow *c* and a supply pipe *d* supplying cold water whereby the water in the tank is kept cool.

e is a paddle wheel having twelve paddles *f*, the spindle being journaled at *h* by 80 means of a shaft in a long bearing, and having at its upper extremity a ratchet wheel *i*.

On this ratchet wheel *a* pawl *j* is provided the carrier *k'* of which is clamped 85 to a rope *k* by a clamp *l*. The carrier *k'* is rotatably secured on the shaft which carries the paddle wheel and the pawl *j* is pivotally secured to said carrier. The rope is given a reciprocating motion by means 90 of the connecting rod *m* working in conjunction with a lever *n* pivoted to a fixed bracket *o*. The connecting rod is pivoted to the lever at *p* and the rope is fixed to it at *q*.

The rope is kept taut by means of a lever *r* pivoted to a bracket *s* and having weights *t* applied to a platform *u*.

The rope is fixed to the lever *r* at *v*. The wheel *w* is suitably geared to the motor 100 driving the band conveyor *x*.

In action the wheel *e* conveys ash and clinkers from the tank *a* and discharges them onto the band conveyor *x*.

The clamps *l* are readily detachable so that where there are several sets of extractors driven from one rope, any one can be placed out of action as desired.

5 I claim:

1. Apparatus for removing ashes comprising a tank adapted to be partly filled with water and adapted for disposition under an ash hopper, one side of said tank 10 being inclined at an angle of approximately 45° and extending above the level of the water; a bearing located above the water level and secured to the side of the tank opposite to said inclined side; a paddle 15 wheel having a shaft journaled in said bearing, said wheel being adjacent to and its plane of rotation being parallel to said inclined side; a ratchet and pawl mechanism for intermittently operating said wheel to 20 remove the ash from the tank over the edge

of the incliner side; and means for operating said pawl.

2. Apparatus for removing ashes comprising a tank adapted to be partly filled with water and adapted for disposition under an ash hopper, one side of said tank being inclined and extending above the level of the water; a bearing secured to the side of the tank opposite to said inclined side, said bearing being entirely above the level of the water in the tank; a paddle wheel having a shaft journaled in said bearing, said wheel being adjacent to and its plane of rotation being parallel to said inclined side; and means for operating said wheel 30 to remove the ash from the tank over the edge of the inclined side.

In testimony whereof I affix my signature.

ALBERT HOSSACK.
